Application September 11, 1940, Serial No. 356,241

12 Claims. (Cl. 36—59)

This invention relates to improvements in shoe soles.

One object of the invention is to provide a sole construction provided with improved means for attaching cleats or calks to the sole.

Another object of the invention is to provide a sole construction embodying flexible metal plates to which cleats or calks are so anchored that impacts or stresses on the calks are distributed to the sole so as to avoid the formation of relatively definite lines of flexure or cleavage in the plates and as to permit the normal transverse flexing of the sole as the weight thereon is shifted progressively toward the toe during use.

Another object of the invention is to provide a shoe sole construction embodying calks for athletic or the like use which avoids the imposition of vertical calk impacts on relatively small superjacent portions of the sole and thereby assures not only more comfort to the wearer but provides greater durability as well.

Another more specific object of the invention is to provide a sole construction comprising a metal calk-anchoring plate and attaching means for calks which do not impose destructive stresses on the plate at the points of anchorage thereto as the calks are deflected from normal positions during use.

Other objects of the invention relate to various features of construction and arrangement of parts which will be apparent from a consideration of the following specification and accompanying drawing, wherein:

Figure 1 is a bottom plan view of a shoe sole embodying the present improvements, part of the sole being broken away;

Figure 2 is a side elevation, partially in section, of the shoe sole shown in Figure 1;

Figure 3 is a perspective view of a calk or cleat in detached relation;

Figure 4 is a broken sectional view through a calk as on line 4—4 of Figure 1;

Figure 5 is a broken sectional view illustrating a modification of the structure shown in Figure 4;

Figure 6 is a similar vertical sectional view through a modified sole and calk construction;

Figure 7 is a broken sectional view of an additional modification of the improvements;

Figure 8 is a plan view of another embodiment of the novel sole construction;

Figure 9 is a section taken on line 9—9 of Figure 8; and

Figure 10 is a perspective view of a calk of modified form.

In Figures 1, 2 and 4 of the drawing, a sole 10 is shown formed of flexible or resilient material, preferably of molded rubber composition. Disposed within the sole between the upper and lower surfaces thereof are two flexible plates 11 and 12. These plates may be of sheet metal, the former being located in the forward portion while the latter is in the heel portion of the sole. The plates preferably are formed of metal sheets having surfaces such that the rubber composition when vulcanized will adhere firmly to the same. For example, the steel may be treated by known methods, such as by one which produces a surface crystallinity which enables the rubber to bond to the plates during the vulcanization process. In addition to vulcanizing rubber in enveloping relation to the plates, calk-anchoring members also are enveloped in the rubber. Such members are, in the embodiment of the invention illustrated in Figures 1 to 4, in the form of threaded members 13 which extend through perforations or openings 14 in the respective plates 11 and 12 and have retaining or anchoring flanges or heads 15 which overlie the marginal portions 20 of the plate at the respective openings 14. The lower ends of the members 13 are shown as provided with lower flanges 16 which are embedded in bosses or calk seats 17 which are integral with the molded material of the sole proper.

Calks or cleats suitable for use with the above described sole construction are designated generally by the numeral 18, one of the calks being shown in detached relation in Figure 3. The body of the calks is formed of a firm but resilient molded rubber composition or other suitable material. Embedded in each of the calks 18 and firmly anchored thereto is a stud 19 having a threaded section 20 extending from the upper end of the calk. It will be apparent that the calks can be attached to the sole merely by screwing the threaded studs into the threaded interiors of the anchoring members 13. By screwing them firmly into position, the calks as well as the calk bases 17 can be compressed slightly, thus placing adequate tension on the threaded members to resist loosening of the calks during use. For the purpose of more securely attaching the calks to the sole, the contacting faces of the calks and the calk bases illustrated have complementary formations of polygonal or circular configurations which increase the frictional engagement thereof when the calks are firmly turned into seating position. For example, in Figures 3 and 4 the lower faces of the calk bases are provided 45 with circular or, as shown, frusto-conical recesses 55 with circular or, as shown, frusto-conical recesses

17^a while the upper faces of the calks are provided with circular or, as shown, frusto-conical projections 18^a. The projections preferably are of such diameter as to fit snugly within the recesses or such as to distend the rubber material surrounding the recesses and compress the projections slightly as the latter are forced into seating relation and thus set up forces which further resist any tendency of the calks to become loose during use. The calk shown in Figure 10 has a protuberance 18^b that is polygonal in plan view and is adapted to seat in a complementary recess (not shown) in a calk base, the flexibility of the base material being such as to enable the calk to be screwed into firm contact as in the above described embodiment of the invention.

As illustrated in Figure 4 the flanges or heads 15 of the calk-anchoring members 13 are embedded in the portion of the rubber of the sole which lies above the plates 11 and 12, the rubber preferably being bonded to such heads. It will be noted that the apertures or perforations 14 of the plate are of such diameter in relation to the shanks of the anchoring members 13 that the anchoring members are enabled to tilt or pivot or move upwardly with reference to the respective plates.

Figure 5 illustrates a modification of the construction shown in Figure 4. In Figure 5 it will be noted that the upper flange 15 of the anchoring member 13 is spaced from the upper surface of the plate 11 by rubber designated 10^a which is a part of the sole material. The flange 15 thus is embedded in the flexible sole material 10^a which further cushions relative movement of the flange with respect to the plate and distributes to a greater area of the plate those stresses imposed on the plate as the flange indirectly pivots thereon.

By the above described features of construction and arrangement of parts, certain desirable results are accomplished, having to do not only with durability of construction but also with the comfort of the user of shoes provided with such soles. For example, if an impact on a calk is directed vertically upward, the cushioning action of the resilient material of the calk and of the superjacent portion of the resilient sole material beneath the respective plate not only functions to absorb the impact but actually distributes the force thereof over a substantial portion of the plate. This distribution of forces is augmented by reason of the bonding of the sole material to the plates. While the calk attaching means, that is, the anchoring members 13 and the studs 20, may tend to rise relative to the plate as the calk and sole materials are compressed, as above-mentioned, such relative movement is further resisted to some extent by the upper portion of the resilient sole material which overlies the heads or flanges 15 of the members 13, which material, as stated, preferably is bonded to the heads 15. Hence the inner portion of the sole material, that is, the rubber material above the plate or plates participates in cushioning and distributing shocks on the calks. It will be seen that the plates are not subjected directly to the forces of impacts transmitted to the attaching means since the members 13 can move relative to the respective plates and hence definite cleavage lines in the plates are not established nor is fatigue of the metal of the plates caused by successive vertical impacts imposed on the calks.

Where the calks are subjected to lateral or angular stresses tending to deflect them from

normal position, the resultant angular movements of the attaching means do not impose destructive bending stresses on the plates due to the fact that the plate apertures are of such diameter as to accommodate such movements of the members. The heads or flanges of the anchoring members 13 tend to tilt or pivot with respect to the upper surface of the plate as a calk is laterally deflected due to the fact that a portion of the periphery of the heads 15 on the side of origin of the imposed stresses will contact the plate and so act as the center of moments. Such points of contact are spaced radially from the respective perforations of the plate a distance dependent on the radius of the heads which, as will be noted, are such as to avoid imposition of such stresses at the margins of the perforations. Formation of cracks in the plate extending from the perforations or deformations in the plate adjacent the perforation are thus substantially avoided by the improved construction.

Where the calks and the contacting portions of the sole are of resilient material, they tend to absorb the lateral as well as the upward components of the laterally applied forces and to distribute them to relatively large areas of the plates as above mentioned, and hence lessen the likelihood of forming cleavage lines in the plate. The tilting or pivotal movement of the members 13, as above mentioned, is resisted also by the superjacent portion of the sole material. It will be apparent, therefore, that while the plates afford means for anchoring the calk attaching members the latter do not impose directly or localize at or adjacent the points of attachment or contact therewith the numerous upward and lateral stresses encountered by the calks during use of shoes embodying the improvements but due to the co-action of the parts described the applied forces or stresses are distributed over substantial areas which not only renders the construction more durable but more comfortable as well. When the calks are firmly attached in position on the sole, lateral stresses imposed on the calks are transmitted directly from the upper surface of the calk to the contacting portion of the sole but are not so directly transmitted by the calk attaching means and hence the studs are not readily bent during use. However, the studs are reinforced or stiffened by the anchoring member 13. Such reinforcement extends from the upper end of the studs down to a line adjacent the lower surface of the sole material and hence the studs are adequately stiffened at the portions most subjected to bending stresses upon the imposition of lateral impacts on the calks.

In the embodiment of the improvements shown in Figure 6, the sole 21 has embedded therein a calk-anchoring plate or plates 22 similar to plates 11 and 12 above described. The plates 22 are provided with perforations 23 for accommodating the shanks of threaded studs 24, the heads of which overlie the marginal portions of the plates 22 surrounding the respective openings 23 and preferably are substantially flush with the upper surface of the sole material beneath the plates 22. Nuts 25 on the studs 24 are spaced from the plates 22 by the intermediate portions 26 of the sole material which not only cushions the plates from the effect of vertical thrusts imposed on the nuts but also serves to disperse such shocks or forces throughout and to dissipate them in relatively large superjacent areas of the plates.

The calk 27 has embedded therein a nut 28 for

receiving the threaded portion of the stud and at the upper surface of the calk there is provided a recess 29 for accommodating the exposed portion of the nut or anchoring member 25. Stresses imposed on the calks 27 during use are partially absorbed by the calks and partially by the sole material disposed beneath the plates 22. Such stresses are distributed to the sole over substantial areas of the sole as will be seen. Where the impacts imposed on the calks are sufficient to tend to cause the studs to move upwardly with reference to the plates, such movement is accommodated by reason of the fact that the studs are not rigidly attached to the plates and hence such imposed stresses do not tend to distort or flex the plates to or adjacent the perforations 23 therein, and thus the formation of cleavage lines passing through or originating in the perforations is avoided. Lateral stresses imposed on the calks may tend to cause the studs to move pivotally slightly, in which instance the calks may pivot at points on the heads which bear directly or indirectly on the upper surfaces of the plates. Such points, however, are spaced radially from the perforations and thus do not tend to deform the metal of the plates at the margins of the perforations. Not only does the material of the calks and the superjacent portions of the sole material tend to absorb such stresses but excessive lateral deflection of the calk attaching means is further resisted by reason of the fact that the anchoring members 25 are partially embedded in the sole material and hence such lateral stresses exert forces on the members 25 which tend to compress the lower portion of the sole material on the side of the members 25 opposite the origin of the imposed stresses.

It will, therefore, be seen that while the plates in the embodiments of the invention disclosed can flex transversely and thus permit the normal flexing action of the sole as the weight of the wearer shifts from backward and forward in use, the stresses imposed on the calks are not transmitted through the attaching means directly to the plates. The distribution to relatively large portions of the sole of calk-imposed stresses not only renders the sole more comfortable but avoids the imposition of destructive forces on relatively small areas of the plates.

In Figure 7 the plate 11^a is shown as having downwardly offset or embossed portions 11^b surrounding the receiving openings for the calk-attaching means, one opening only being illustrated. By so forming the plate, not only is it strengthened at the perforations but concavities are provided for the flush receipt of the heads 24 of the studs 23, or the flanges 15 of the member 13 where the anchoring means shown in Figure 4 are employed. The flexible sole material 10^b on the upper surface of the plate 11^a extends into the concavities and thus cushions the heads of the studs or the upper flanges of the members 13 as described above with respect to the embodiment illustrated in Figure 5.

The sole construction illustrated in Figures 8 and 9 of the drawing may correspond with the construction shown in either of the above described embodiments except that in the form shown in Figures 8 and 9 the outer surface of the sole is provided with a rib 30 integral with the lower portion of the sole material which reinforces the latter along the marginal portions of the plates 31 and 32. The reinforcing rib reduces the likelihood of the sole material being cut by the edges of the plates, particularly the forward

or sole plate, as the latter flexes in use and also serves to indicate the seam line as well as to protect the seam.

It will be observed therefore that the above described embodiments of the invention produce certain advantageous results over prior art structures wherein the calk-attaching means were directly attached to the plates as by threaded engagement therewith, or were provided with heads which were anchored merely in the flexible rubber or composition sole material beneath the plates.

While I have shown and described certain embodiments of my improvements for the purpose of illustrating the invention, it will be apparent that various modifications thereof may be resorted to without departing from the spirit of the invention.

Having thus described the invention, what I claim as new and desire to cover by Letters Patent is:

1. A shoe sole comprising a perforated plate and resilient sole material on the lower side thereof, calk-anchoring members each movably contacting the upper surface of the plate and extending downwardly through a perforation into embraced relation with said resilient sole material, and calks of resilient material each provided with means for engaging a calk-anchoring member for retaining the respective calk in compressive contact with the resilient material of the sole for cooperation with the latter in absorbing stresses imposed on the calks in directions tending to move the respective anchoring members relative to the plate.

2. A shoe sole comprising a perforated plate and resilient sole material on the lower side thereof, threaded calk-anchoring members each movably contacting the upper surface of the plate and extending through one of the perforations and embraced by the resilient material on the lower side of the plate, and calks of resilient material each provided with threaded means for threadedly engaging a calk-anchoring member whereby the resilient material of the calks can be tightened into compressive contact with the resilient material of the sole for cooperation with the latter in absorbing stresses imposed on the calks tending to move the respective anchoring members relative to the plate.

3. A shoe sole of molded flexible material having a flexible perforated plate embedded therein, calks for the sole, and calk attaching means each having a portion embedded in a calk and a cooperating portion extending through a perforation of the plate and movable relatively thereto.

4. A shoe sole of molded resilient material comprising a flexible perforated plate embedded in the sole material, calks for the sole, and calk attaching means for securing the calks to the sole, said means comprising members secured to the calks and cooperating members extending through perforations of the plate and movable laterally within said perforations, said last mentioned members being so embraced by the flexible sole material at the lower side of the plate that said material cushions the relative movement of the embraced members with respect to the plate.

5. A shoe sole of flexible rubber composition, a perforated flexible metal plate embedded therein, calks for the sole, and means for attaching the calks to the sole comprising members secured within said calks and cooperating members each extending through a perforation in the plate and of a diameter affording relative

movement within the perforation and provided with anchoring portions both above and below the plate, at least one of said portions of each of said members being embraced by the flexible composition of the sole whereby the latter cushions upward and lateral movements of the members imparted thereto by stresses imposed on the calks.

6. A shoe sole of flexible material, a perforated flexible metal plate embedded therein, calks provided with threaded attaching members, and means for anchoring the calks to the sole comprising a threaded member for threadedly receiving the threaded member of a calk and each extending through one of the perforations of the plate and of a diameter affording relative movement thereof within the respective perforation, each of said members having a head extending over the portion of the plate surrounding the respective perforation and a lower portion embraced within the flexible material of the sole below the plate.

7. A shoe sole of flexible material having a perforated plate disposed between the upper and lower surfaces thereof, calks of resilient compressible material, and attaching means for the calks anchored to the sole above the plate comprising members provided with heads overlying the margins of the perforations and each extending downwardly through one of said perforations and of a diameter permitting the heads of the members to pivot on the plate at points radially removed from the margins of the respective perforations, and members carried by the calks each for engaging one of the attaching members of the sole for retaining the calks in compressed relation in contact with the sole.

8. A shoe sole of resilient material provided with a perforated resilient metal plate disposed between the upper and lower surfaces thereof, calk anchoring members having shanks extending downwardly through said perforations and each provided with heads overlying the margins of the respective perforations, the portions of the shanks of said members within said perforations being of such diameter as to enable the members to pivot with respect to the plate about marginal portions of the respective heads, and calks each provided with a member for engaging a shank of one of the anchoring members of the sole and retaining the respective calk in

contact with a lower portion of the resilient sole material.

9. A shoe sole comprising a lower surface of resilient material, a perforated plate disposed above said surface, calks for the sole, and means for attaching the calks under tension against the resilient material of the sole comprising cooperating pairs of threaded members, one of each pair being carried by a calk and the other member having a shank extending downwardly through and of smaller diameter than a perforation of the plate and provided with a portion having pivotal anchoring contact with the upper surface of the plate to enable the calk to pivot about said portion under restraint of the contacted portion of the resilient sole material.

10. A shoe sole comprising a metal plate and resilient sole material on the lower side thereof constituting the lower surface of the sole, calks movably the sole, and means for attaching the calks under compression against the material of the sole whereby relative movements of the calks with respect to the sole are cushioned, said means comprising threaded members pivotally attached to the plate and cooperating threaded members carried by the calks.

11. A shoe sole provided with flexible calk seats on the lower surface thereof, calks for the sole and cooperating threaded members carried by the sole and calks for removably securing the calks in contact with the seats, the contacting surfaces of the seats and calks having coacting frusto-conical formations which mutually exert opposed radial forces on the seats and calks for resisting retrograde threaded movement of the calk.

12. A shoe sole comprising a perforated plate and resilient sole material on the lower side thereof, calk-anchoring members each movably contacting the upper surface of the plate and extending downwardly through a perforation into embraced relation with the said resilient material, and calks each provided with means for engaging a calk-anchoring member for retaining the respective calk in compressive contact with the resilient material of the sole for cooperation with the latter in absorbing stresses imposed on the calks in directions tending to move the respective anchoring members relative to the plate.
